UNITED STATES PATENT OFFICE.

BERNARD MULLER-THYM, OF KANSAS CITY, MISSOURI.

HORIZONTAL-WICK BURNER.

Application filed June 8, 1920. Serial No. 387,367.

To all whom it may concern:

Be it known that I, BERNARD MULLER-THYM, a citizen of the United States, and resident of Kansas City, in the county of Jackson and State of Missouri, have invented a certain new and useful Improvement in Horizontal-Wick Burners, of which the following is a complete specification.

This invention relates to burners of that class exemplified in my Patent No. 1335011, dated March 30, 1920, in which a long flexible wick is drawn through a body of oil and wound upon a slowly turning drum or arbor, the flame being supported on the wick at an intermediate point, i. e., at the surface of the body of oil.

Sanctuary lights are so-called perpetual lights but are in fact merely temporary and burn at most but for a few days at a time, the consumption of the wick or the oil resulting in extinguishment of the light. Sanctuary lamps of the type mentioned in the patent above identified, have been operated continuously for three or four weeks without attention, but such lamps I have found not fully satisfactory because they produce a smoky flame. For sanctuary lamps, the small size of the flame is unobjectionable, in fact is desirable, but such a structure for producing light and heat, is inadequate. With a vertical wick of the type shown by said patent, the oil is absorbed to the highest point of the flame where the oxygen of the air combines with the gases produced by the decomposition of the oil, and the flame does not effectively reach such gases and hence imperfect combustion occurs.

A vertical wick is also objectionable because the transformation of the oil to gas will result in the deposit of non-consumable matter on the wick which ultimately will destroy the capillary properties thereof. The objections raised to the vertical type of wick of course do not apply particularly to candles, as in a candle the wick as soon as relieved of its support by the tallow or wax, will bend to a point at one side of the flame where the white part thereof will burn the deposits or carbons, and the wick is supplied to the flame in fresh condition continuously by the consumption or burning away of the body of tallow or wax.

I have found that by using a wick horizontally at the point where it is to burn, no oil is fed to the flame except in the lower

part thereof so that the ascending gases generated at such point are not interfered with and readily mix with the oxygen of the air. In this type of wick, it is preferable to provide the body of cotton or other consumable material, with a thin flexible non-consumable core. This wick is fed endwise by automatic mechanism, such as a clock-work, and the speed of travel determines the width of the flame and hence the volume of light and heat produced thereby. In this construction the deposit of carbon will stop the flow or advance of oil in the wick and thus give the outer or advanced part of the flame an opportunity to burn such deposit if the wick is of a non-combustible nature. On the other hand if it is of a combustible nature the body of the wick will burn completely from the core. The invention also comprises a guard for setting up a circulation of air forwardly toward the flame and thus limit the width of the flame by preventing the same backing up upon the wick.

With the general object in view of producing a burner for producing a so-called perpetual flame, especially for the sanctuary and in places difficult or inconvenient of access, as in light houses, mountain signal stations and the like, the invention will now be described by reference to the accompanying drawing which illustrates one form of construction which I have devised for embodying the proposed improvement, after which the features therein deemed to be novel will be particularly set forth and claimed.

In the accompanying drawing:

Figure 1 represents a view partly in vertical section and partly in side elevation, of a sanctuary lamp embodying the invention, the mechanism for operating the wick and for supplying the bowl of the lamp with oil, being located at the opposite side of a partition from the bowl or body portion of the lamp itself.

Figure 2 is a top plan view of the construction shown by Figure 1.

Referring to the drawing in detail, 1 indicates the bowl of the lamp, the top of which is shown as removable and provided with a tubular guide 2, vertically over a chambered portion 3 of the bowl.

Located within the chambered portion 3 so as to be capable of revolving therein is a reel 4 and wound upon said reel is a wick comprising a flexible metal core 5 and a

body 6 of cotton or the like covering said core.

7 is a depending tube extending through the guide 2 and provided at its upper end 5 with an elbow shaped portion 8, the latter being enlarged and internally threaded at its lower end at 9 where it is screwed to the upper end of tube 7 and by resting upon the top of the bowl, forms a support for 10 said portion 7, and the lower end of the latter is flared or bell shaped as at 10.

The upper end of the elbow shaped or curved portion 8 of the tube is disposed horizontally and fitted within and spaced 15 from the conical guard 11, provided with a depending leg 12 secured to the top of the bowl, the front or reduced ends of the tube 8 and the guard 11 being disposed vertically over a perforated depressed portion 13 in 20 the top, so that any oil which may drip from the front end of the tube and guard shall pass back into the bowl.

In operation the wick is ignited at the front end of the said tube and guard, and 25 the body or absorbent portion of the wick will burn from the core at such point, the core extending forward to a winding drum or arbor 14 arranged vertically and journaled in the sleeve portion 15 formed on the 30 top of the bowl at the inner side thereof. A pulley 16 is mounted on said drum or arbor and is connected by a flexible belt or the like 17 to a pulley 18 rotatable with a beveled gear of a clock work 19 mounted 35 in a suitable casing 20 at the opposite side of the partition 21 from the bowl. The gearing of the clockwork may be driven by an ordinary clock spring, not shown, or by any other suitable power.

40 Superposed with respect to the clockwork mechanism, is a tank 22 for containing any required quantity of oil, and provided with a filling opening 23. At the lower end of the tank is a discharge tube 24 leading to 45 the interior of the bowl, and said pipe is controlled by a suitable valve 25. A second pipe 26 leads from the upper end of the tank to the bowl at a point where the oil level in the latter is to be maintained, and 50 is controlled by a valve 27. It will be understood that the oil feeds by gravity to the bowl and that as soon as its level covers the connected end of the pipe 26, the feeding operation stops, and that as consumption 55 lowers said level slightly, the supply from the tank is immediately replenished through the pipe 24.

Assuming that the parts are arranged as shown and that the clock work is in operation 60 and feeding the wick slowly in the direction indicated by the arrow, Figure 1, it will be seen that the wick is ignited at the front end of the guard 11, will burn at such point as indicated, it being understood 65 that the speed of travel of the wick

is ordinarily imperceptible to the eye, and that the absorbent portion of the wick is consumed and hence limits the advance of the flame towards the drum or arbor. It will also be noted that the heat of the flame 70 will set up a circulation of air through the guard 11 and around the tube 8 toward the flame and hence guard against the widening of the flame toward the tube 8 and tending to keep the wick cool adjacent the flame. 75

The tube 7 not only serves as a guide for the wick but tends to assist the capillary action especially when heavy oil is used, and also to prevent the wick from being charged with an excess quantity of oil, any 80 drippage however, which may occur at the front end of tube 8 dropping down upon the perforated sunken portion 13 of the top and passing back into the bowl. With a burner of this character the speed of 85 travel of the wick will determine the width of the flame and hence the volume of light and heat generated and it will be understood that when made of large size and used with proper reflectors, the light may be employed for signal purposes or the like and that the length of the wick and the continuance of its feeding movements are the factors which determine how long the light may be maintained without attention on 95 the part of those in charge.

It will be noted that by producing the flame on a horizontal portion of the wick, and imparting movement to the latter, the width of the flame cannot only be controlled 100 but that oil is fed to the flame only at the lower part thereof so that the gases produced at such points ascend without interference and are therefore mixed with the oxygen of the air to produce perfect combustion. It will also be understood that any solid deposits or carbons left in the wick will not stop the flow of the oil as at the outer part of the flame such deposits will burn off if the wick is of a non-combustible nature. If the body of the wick 110 however, is of a combustible material, such as cotton, such body will burn off completely and leave the core to travel to and wind upon the drum or arbor, as indicated by 115 Figure 1.

From the above description it will be apparent that I have produced a burner embodying the features of advantage set forth as desirable in the statement of the object 120 of the invention, and which is susceptible of modification in various particulars without departing from the principle of construction and mode of operation involved, or from the spirit and scope of the appended 125 claims.

What I claim is:

1. A burner comprising an oil receptacle, a reel, a flexible wick extending through the oil in the receptacle from the reel, a wick 130

guide for the oil saturated wick and winding drum spaced horizontally apart, and means for confining the burning zone of the wick to a point between the drum and said oil receptacle.

2. A burner comprising a liquid fuel receptacle a wick guide and winding drum spaced horizontally apart, a wick extending through the fuel receptacle and from said 10 guide to said drum and having a flexible non-burning core, and means adjacent said guide for confining the burning zone of the wick to a point between the guide and drum.

3. A burner comprising a bowl, means for 15 keeping the bowl charged with oil to a suitable level, a driven winding drum, a reel, a flexible wick extending through the oil in the bowl from the reel to the drum, guiding means for the wick to maintain part of 20 same between the bowl and drum, in a horizontal position, and means for confining the burning zone of the wick to a point between said drum and bowl.

4. A burner comprising a bowl, a tube 25 extending up through the top of the bowl and terminating in an elbow portion, a driven winding drum, a reel, a wick extending from the reel through the oil in the bowl and through said tube to said winding drum and disposed substantially horizontally beyond the free end of the elbow portion of the tube, the top of the bowl having a perforated depressed portion below the free end of the said elbow portion of the tube.

5. A burner comprising a bowl, a tube extending up through the top of the bowl and terminating in an elbow portion, a driven winding drum, a reel, a wick extending from the reel through oil in the bowl and through said tube to said winding drum and disposed substantially horizontally beyond the free end of the elbow portion of the tube, and a conical guard enclosing and spaced from the free end of said elbow portion of the tube and disposed with its attenuated end adjacent the wick where the same emerges from said tube.

6. A burner comprising a bowl, a tube extending up through the top of the bowl and terminating in an elbow portion, a driven winding drum, a reel, a wick extending from the reel through the oil in the bowl and through said tube to said winding drum and disposed substantially horizontally beyond the free end of the elbow portion of the tube, the top of the bowl having a perforated depressed portion below the free end of the said elbow portion of the tube.

In witness whereof I hereunto affix my signature.

BERNARD MULLER-THYM.
